ATTORNEY

UNITED STATES PATENT OFFICE

FRANCIS CHARLES SCHMID, OF THE UNITED STATES NAVY

SELF-INDICATING REFILLABLE ELECTRIC CARTRIDGE FUSE

Application filed August 29, 1929. Serial No. 389,259.

This invention relates to electric fuses, and more particularly to fuses of the self indicating and refillable type.

Electric cartridge fuses as heretofore used have included certain disadvantageous features; for instance, when the fuse has blown it has been necessary to provide an entirely new fuse, due to the fact that the fusible element has been ruined; or else it has been necessary to solder the fusible link or other element, which has necessitated a considerable expenditure of time and labor. Also, when such fuses have been of the self indicating type it has been necessary to use particular care in installing the fuse so that the indicator will be visible at the front of the panel board.

Certain types of fuses have been heretofore constructed in which it has been necessary for the electrician to make a considerable search on a panel containing many fuses in order to locate the fuse that has blown, these fuses thus being of the "blind" type. Other fuses of the indicating type have included features whereby the electrician could determine the particular fuse that has blown, but such fuses have been more expensive than those of the "blind" type, and when blown have included no provision for being refilled, the fuse being discarded and replaced with a new one at additional expense. To solder the broken ends of a fusible link has heretofore been impossible with certain types of fuses, and impracticable with others by reason of the time required for such purpose. Heretofore, when fuses have included provision for replacement of the fusible element they have always been of the "blind" type, having the disadvantage above referred to.

The primary object of my invention is to enable the fuse to be constructed so that it will be self indicating and also so that the fusible link element will be replaceable with a new fusible element whenever it has been destroyed, so that the same cartridge can be used over and over again, and also to enable the fuse to be constructed so that when the fuse has blown, the indicator or flag will be visible in any position of the fuse, whereby the installer can quickly position the fuse be-

tween the contacts without taking time to find the indicator side and position said side at the front.

A further object is to provide a fusible element or link which can be kept on hand in quantities for replacement purposes.

Still further objects are to simplify and improve the construction of electric cartridge fuses, to reduce the cost of manufacture of the fuse as a whole, as well as the cost of replacement, and to provide an electric cartridge fuse which will be self indicating and refillable and as well, quick acting and arcless.

Other objects and advantages of the invention will be hereinafter specifically pointed out, or will become apparent, as the specification proceeds.

With the above indicated objects in view, the invention resides in certain novel constructions and combinations and arrangement of parts, clearly described in the following specification and fully illustrated in the accompanying drawing, which shows an embodiment of the invention as at present preferred.

In the drawing:

Fig. 1 is a perspective view of the fuse body.

Fig. 2 is a longitudinal sectional view through the fuse, showing the parts in operating position.

Fig. 3 is a partial sectional view taken on the line 3-3 of Fig. 2.

Fig. 4 is a partial longitudinal sectional view similar to Fig. 2, showing the parts in the position assumed when the fusible element has blown and the indicator or flag hence caused to assume its indicating position.

Fig. 5 is a perspective view of the refiller plate.

Fig. 6 is a perspective view of the renewable fusible link.

The electric cartridge fuse 10 in this instance includes a cylindrical shell or body 11, preferably formed of insulating material, and having a bore or chamber 12. A cylindrical head 13 is secured at one end of the shell. This head 13 has a smaller diameter

screw-threaded portion 14 and is provided with an axial aperture 15 communicating with the inner chamber 12. The interior walls of the head 13 are inclined at opposite sides, as seen at 16 and 17, so that they converge from the end of chamber 12 toward the axial aperture 15.

At the opposite end of the shell 11 a rim 18 is provided; and a cylindrical housing 19, having a chamber 20, is adapted to be removably secured to the end rim 18 by means of one or more bayonet joints as seen at 21', though any other approved form of securing means may be used for the latter. The housing 19 and rim 18 are formed of conducting material such as brass or copper.

Within the housing chamber 20 I provide an indicator device which in this instance is in the form of a disk 21 including an annular 20 flange and having an attaching device, such as a hook 22, secured at the central portion of the disk and arranged to extend in the direction of the shell chamber 12. Resilient means, such for instance as a compressible 25 spring 23, are provided between the indicator disk 21 and the rim 18 for the shell or body 11.

A suitable fusible element is adapted to be secured to the indicator disk 21, and in this instance I provide an elongated link 24, 30 formed of suitable fusible material. This link 24 has a reduced portion or neck 25 about midway of its length, though the latter may be provided at any desired point, and securing means in the form of an aperture 26 at 35 one of its ends. The hook 22 is adapted to be passed through the aperture 26 to hold this end of the fuse in position.

The fuse link 24 being attached at one of its ends as described, the housing 19 is placed 40 over the end of the shell 11 and secured in place at the bayonet joint 21', the free end of the fuse link extending through the chamber 12 and aperture 15. During this passage the fuse link is guided into and past the aperture 15 by the inclined wall portions 16 and 45 17. The fuse link is drawn outward, compressing the spring 23 to which the opposite end of the fuse link is secured, and bringing the spring 23 into contact with the metallic rim 18, to cooperate with the hook 22 in establishing electrical connection between the housing 19 and fusible link 24. The spring 23 may be compressed part way, as seen in Fig. 2 and electrical connection will still exist 50 because the base of the spring engages the rim 18. The outer, free end of the fusible link is adapted to be held in place at the outer end of the head 13 by a removable securing or refiller plate 28 having an inwardly extending lug 29 adapted to engage the link 24 with a wedging action in the axial aperture 15. The free end 30 of the fusible link is then bent over the outer surface of the refiller plate 28 as seen in Fig. 3, after which a cylindrical cap 31 is screwed on to the threaded 55

portion 14 of the head 13 so that the inner face of the cap securely clamps the end of the fusible link against the refiller plate. In this position of the parts, electrical connection is established between the fusible link, 70 the cap 31 and head 13, and the fuse is ready for use. The cap 31 preferably has a slot 32 for use in applying a screw driver to tighten the cap 31.

Overload of electric current in the circuit 75 will cause the fusible link to melt at its weakest point, 25, and this parting of the link will cause the spring 23 to be released, breaking the electric circuit. Expansion of this spring forces the indicator disk or flag 21 80 from its normally concealed position to its outer limit against the outer end of the housing chamber 20, as seen at 33 in Fig. 4. A plurality of window openings 34, 35 and 36 are provided through the side walls of the 85 housing 19 so that when the circuit has been broken and the indicator or flag forced outward as just described, the flange of the flag, which is indicated by the reference numeral 27 will be visible through the windows 34, 35 90 and 36. These windows are located at spaced points around the wall of the housing 19 so that at least one of the windows will be located toward the front regardless of the axial position of the fuse when placed in position 95 between its respective contacts on the panel board.

To refill the cartridge and enable the same to be used over again, the cap 31, refiller plate 28, and housing 19 are disassembled, as will 100 be readily understood, and the separated ends of the fusible link withdrawn from the shell 11. The end of the fusible link connected to the hook 22 is then withdrawn and a new 105 fusible link of the same construction, as seen in Fig. 6, is attached to the hook 22 and the parts are reassembled as hereinabove described.

It will be understood that the fusible link 110 24 may be constructed of wire or other equivalents as well as of thin leaf metal as shown herein.

My present invention provides a fuse which is self-indicating, refillable, and as well, arcless, because the construction enables the broken ends of the fusible link to be instantly separated through the action of the compressible spring. The fuse thus presents in a simplified unit, the combined advantages of practically all types of electric cartridge fuses. 115 It can be rated for any voltage or amperage; and it operates and indicates instantly. When it is desired to renew the fusible element the aid of a screw driver is all that is required. The refills can be furnished in 120 quantities for each fuse, at a trifling expense, so that fuses once purchased can be maintained in operating condition by being refilled whenever necessary at an expense that is practically insignificant. The present im- 125 130

provements make for great convenience in use and economy in cost and upkeep.

The hereinbefore described construction admits of considerable modification without departing from the invention; therefore, I do not wish to be limited to the precise arrangements shown and steps described, which are, as aforesaid, by way of illustration merely. In other words, the scope of protection contemplated is to be taken solely from the appended claims, interpreted as broadly as is consistent with the prior art.

What I claim as new, is:

1. An electric cartridge fuse comprising a shell, a head secured at one end of said shell, said head having an axial aperture, a housing at the opposite end of said fuse, an indicator disk positioned in said housing, resilient means interposed between said indicator and the end of said shell, a replaceable fusible link having one of its ends attached to said indicator, the opposite end of said link adapted to extend through said axial aperture at the opposite end of the shell, means to hold the end of said fusible link in wedging engagement at said axial aperture, a screw cap on said cylindrical head, said cylindrical housing having a plurality of spaced window openings at the outer sides thereof, whereby the breaking of said fusible link is adapted to release said resilient means and project said indicator outward toward the outer end of said housing and render said indicator disk visible through said window openings.

2. An electric cartridge fuse comprising a shell, a head secured at one end of said shell, said head having an axial aperture, the interior walls of said head having inclined sides converging toward said axial aperture, a housing removably mounted at the opposite end of said fuse, an indicator disk positioned in said housing, a compressible spring between said indicator and the end of said shell, an elongated replaceable fusible link having one of its ends removably attached to said indicator, the opposite end of said link adapted to extend through said axial aperture at the opposite end of the shell, a plate adapted to abut against the outer face of said cylindrical head, said plate having a portion to enter said axial aperture and hold the end of said fusible link in wedging engagement at said axial aperture, the extended end of said fusible link adapted to be bent over the outer side of said plate, a cap adapted to be screw threaded on said cylindrical head to secure the extended end of said fusible link in clamping engagement, said cylindrical housing having a plurality of spaced window openings at the outer sides thereof, whereby the breaking of said fusible link is adapted to release said spring and project said indicator outward toward the outer end of said housing.

and render the edge of said indicator disk visible through said window openings.

3. In an electric cartridge fuse, a hollow cylindrical body, a rim surrounding one end of said body, a housing for said end and being provided with bayonet slots, pins extending from said rim and receiving said bayonet slots for securing the housing to said body, said housing having openings arranged in annular formation about the same, a spring pressed indicator in the form of a disk including an annular flange adapted to show through the openings and mounted for slideable engagement with the housing, a head for the opposite end of said body, a replaceable fusible element disposed in said body, a hook secured to the disk and detachably receiving one end of said fusible element for connecting the latter to the disk, a cap for said head, means received by said head and cooperating with said cap for securing the opposite end of the fusible element to said head, and said fusible element normally holding said disk with its annular flange out of registration with the openings.

In testimony whereof I have affixed my signature.

FRANCIS CHARLES SCHMID.
